one-half to Ladislaus Robaczynski, Brooklyn,
N. Y.

Application June 22, 1937, Serial No. 69,978

Term of patent 7 years

To all whom it may concern:

Be it known that I, Nathan Cooper, a citizen of the United States, residing at Brooklyn, in the county of Kings and State of New York, have invented a new, original, and ornamental Design for a Knitted Vest, of which the following is a specification, reference being had to the accompanying drawing, forming part thereof.

The figure is a front view of a knitted vest, showing my new design, the back of the vest being conventional.

The characteristic feature of my design resides in the combination on the knitted vest disclosed of the specific neck opening and relatively long, diverging waist points in association with short rows of contrasting stitches on the shoulders and lower front quarters, as shown.

I claim:

The ornamental design for a knitted vest as shown and described.

NATHAN COOPER.
